UNITED STATES PATENT OFFICE.

RENÉ PIERRE ALEXANDRE LE GRAND AND ANTOINE MICHEL GARRET, OF PARIS, FRANCE; SAID GARRET ASSIGNOR TO SOCIÉTÉ DE VANOISE, ZIEGLER & P. LANGLOIS, OF ST. MARS-LA-BRIÈRE (SARTHE), FRANCE, A CORPORATION OF FRANCE.

AUTOMATIC DUPLICATING APPARATUS OF THE ROTARY TYPE HAVING AN AUTOMATIC SHEET-FEEDING DEVICE.

Application filed May 19, 1925, Serial No. 31,280, and in France May 21, 1924.

The present invention relates to rotary duplicating apparatus with an automatic sheet feeding device, employing an impression system, which may be either ordinary stencil duplicators or a lithographic arrangement or multigraph impression with direct inking or with ribbon.

This arrangement is provided with an automatic suction feed of the sheets as well as a special apparatus for preventing the pressure cylinder from coming into contact with the printing surface, in the case where a sheet of paper has not been fed into position by the automatic device. A recorder, actuated by the same arrangement, records the exact number of sheets printed.

The invention is illustrated in the accompanying drawings, in which:

Fig. 1 is a vertical sectional view of one form of the invention.

Fig. 2 is an end elevational view thereof.

Fig. 3 is a sectional view similar to Fig. 1 of a modified form of the invention and

Fig. 4 is an end elevation of the form of the invention shown in Fig. 3.

In Figures 1 and 2 the apparatus comprises a stand S on which are fixed two supports 1 and 2 having two bearings in which are carried respectively a crank handle M fixed by the screw 3 and a shaft 4 whose threaded end engages one of the flanges 5 of the cylinder C.

The crank handle M carries at one end by means of the screw 6 a hand stud 8 which can only draw the cylinder in one direction and which automatically returns if the cylinder turns accidentally in the wrong direction.

The cylinder C comprises two circular disks 5 and 7 on which is mounted a cylindrical plate c which is fixed at one end by countersunk screw-heads. This cylindrical plate is prepared so as to render it adaptable for the reproductions which the apparatus has to make.

To the inside of this cylindrical plate, and according to one of the generating lines of the cylinder, is fixed a tube 8, having three holes 9, 10 and 11, which correspond to three holes in the cylinder. The tube 8 carries a

pump P. This air pump P having a metallic cylindrical casing, in which a piston 12 having a leather packing works, has on its under part a small stop valve 13, which obstructs the passage of the air from the body of the pump to the tube 8 when the piston stem 14 forces the latter against the cylinder. A return spring 15, pressing against the cover 16 of the pump body and the head of the piston stem 14, moves the latter from the bottom of the cylinder.

A lever L, connected to the shaft 17, pivoted to projections on the disk 5 and engaged in the head of the piston stem 14, has an extremity E thereof traversing the disk 7 by a radial slot, allowing the pneumatic pump P to work. The extremity E of the lever L contacts with a fixed cam 18 called a snail cam, in such a manner that when turning the cylinder C by means of the crank M, the extremity E mounts on the circumference of the snail cam 18 as far as the point 19 most remote from the centre of the axis of rotation of the cylinder. During the upward movement, the lever L, pivoting at 17, moves the piston 12 as far as the end of the cylinder P, sweeping the air upwardly which was inside the cylinder owing to the leather packing 20 with which the piston is provided.

Continuing the movement of rotation, the lever L by means of the spring 15, is brought back into contact with the cam face, towards the centre of the axis of rotation of the cylinder C, which determines the displacement of the piston 12 and creates a partial vacuum in the pump P. This partial vacuum transmitted by the tube 8 to the holes 9, 10 and 11, will at the desired moment allow the cylinder to come into contact with the sheet of paper before it is printed. This arrangement constitutes the automatic feeding device of the apparatus.

The cam 18, centered on one of the bearings of the support 1 can pivot about the bearing and can be fixed in a convenient position by a milled screw 21. This displacement of the cam 18 has the object of varying within fixed limits the precise point where the lever L can avoid the cam and

consequently regulates the moment when the suction of the sheet of paper should be made in relation to a predetermined position of the cylinder.

Moreover, the lever L can be attached to its end E by a rod touching the cylindrical end and permitting the lever to operate whilst the cylinder C is stationary. It is then possible to operate the pump P by hand, without turning the cylinder C.

The two supports 1 and 2 are provided at their top with two holes 22 and 23, traversed by a cylindrical shaft 24 whose ends have a cylindrical hole bored therethrough perpendicular to the shaft and which allow two cylindrical rods 25 and 26 to slide therein which vertically traverse the holes 22 and 23.

The ends of the rods 25 and 26 are threaded and carry milled nuts 27 and 28 which regulate the tension of the springs 29 and 30 which abut on one side against the frame and on the other against the milled nuts, so that the two cylindrical rods 25 and 26 are constantly pressed downwardly, acting upon the shaft 24. This shaft is rotated by an india rubber or gelatine roller 31, mounted on a copper tube 32 allowing it to turn with slight friction on the shaft 24. Consequently the roller 31, owing to the arrangement described above, is constantly urged downwardly in such a way that one of the generating lines comes into contact with a generating line of the cylinder C. The roller 31 is called the pressure cylinder and is forcibly applied to the sheet of paper to impress it on the cylinder C carrying the composition or stereotype.

The arrangement which is to be described below has for its object the elimination of the so-called dead point to avoid which the roller 31 only comes into contact with the cylinder C carrying the type, if for some reason (bad automatic feed or failure of paper supply or working of the vacuum apparatus) no sheet of paper is interposed between the roller 31 and the cylinder C.

On the disk 7 is mounted an arm 33 pivoted at o. One end of this arm 33 is supported under the lower end E of the lever L. The other end 34 engages a rod 7 which operates cams 35 on the shaft 36. This shaft 36, traversing the cylinder C parallel to one of its generating lines actuates the identical cams 35 at the opposite ends of the cylinder C and shaft 6. The lever L having been raised by the snail cam during the movement of rotation, must not fall to the lower part of its travel should a sheet of paper cover the suction holes 9, 10 and 11, but in the case where a sheet does not, for some reason, cover the holes, the lever L falls to the bottom of its travel and its end E coming into contact with the arm 33 raises it by means of the cams 35, which during the rotation of

the cylinder C becomes vertical to the abutments 38, 39 of the pressure cylinder and raise the shaft 24 of the pressure cylinder until the centres of this shaft come opposite spring clips 40 and 41 which maintain the cylinder 31 in raised position removed from the cylinder C during substantially an entire revolution thereof and until the fixed cams 42 and 43 on each of the disks 5 and 7 become engaged with the claws 44 and 45 of the abutments 38, 39. These latter by reason of the shape of the cams 42 and 43 are drawn downwardly thus bringing the centres of the shaft 24 out of engagement with the claws 40, 41, and allow the cylinder 31 to descend again in contact with the cylinder C. The cam 35, actuated by the lever L through the arm 33, at the same time ensures the raising of the cylinder 31 to displace the projection of the recorder (not shown) if a sheet is not printed.

The apparatus comprises moreover a metal plate 65 which places nearly vertically blank sheets of paper, so that the ends of the sheets come into contact with the steel bar 66 supported by adjustable levers 67 which allows the ends of the sheets to approach the cylinder C without, however, actually making contact which would have the effect of crumpling the sheets.

Two prongs 69 and 70 pivoted to one of the cross bars of the frame 71 through their curved ends, come into contact with the cylinder C, interpose themselves between the latter and the printed sheet of paper, detach it from the cylinder and pass it into a receiver 72 fixed in front of the apparatus. This receiver comprises vertical and horizontal guides similar to those of the plate 65, adjustable to the size of the paper used.

A metal cover may cover the whole apparatus to protect it from dust and to facilitate its transportation.

In the modification shown in Figures 3 and 4, the holes 9, 10 and 11, in the tube 8, are in direct communication through the tube 73, with the annular space 74, formed by the flanged disk 7'. This annular space is closed by a flexible rubber diaphragm 74 held on the flanged disk 7' by means of a washer 75, secured by screws 76. This diaphragm has at its centre a circular hole which can be fixed by means of two metallic washers 77 and 78 against the shouldered end of the piston rod 79. This rod is connected to the end of a rocking lever 80 which can oscillate at 81 on the fixed shaft secured in the support 82.

The other end 82 of this rocking lever acts upon a flat of the rod 84 of the pump. This rod 84 slides in the disk 7' and in the boss 85 formed inside the cylinder. This rod is constantly drawn outwardly by the spring 86 acting on the boss 85 and upon a suitable washer or pin 88 positioned on the shaft 84.

The end of this rod 84 carries a roller 89 rotatable on the pins 90. The circular hollow of the disk 7' communicates by means of the opening 91 with the air outside the holes 9, 10 and 11, which open into the chamber 74' in such a way that the movement of the rubber diaphragm 74 causes a suction of air through the holes 9, 10 and 11.

The flange 5' has on its outer surface at 10 the centre a bearing in which is screwed the stud 4'. This bearing is prolonged to the inside of the cylinder by another bearing of the same diameter on which slides a bush 92 connected to the movable cam 93 by three 15 fingers 94 which traverse the surface of the flange.

The bush 92 has a hole in one end in which 20 engages a rod 95 having two nuts 96 and in the other end a strap 97 pivoted at 98 to the head of the piston rod 79. The rod 95 terminates in the inside of the bush 92 with a cylindrical head on which presses a spring 99 which contacts at its other end with the bush 92.

25 On the outside of the flange 5' is fixed a fixed cam 100 whose shape is such that its exterior diameter and that of the cam 93 form a continuous circular cam.

The cylinder 101 supported by the flanged 30 disks 102 and 103 rotates, through central bushes 104 and 105, on a fixed shaft 106, hinged by a suitable arrangement on forks 107, 108, pivoted to the bar 109. These forks rest, by means of two adjustable screws 110 35 and 111, against levers 112 and 113, fixed to a steel tube pivoting on the cross bar 114. The lever 112 has on its lower surface a roller 115 turning on the shaft 116 fixed to the lever. The position of the roller 115, 40 which has a small shoulder, is such that it contacts with the circular cam constituted by the fixed cam 100 and the movable cam 93. The upper cylinder is operated by a pinion 117 fast on the flange 103; this pinion 45 engages with a pinion 118 on the flange 7' of the lower cylinder so that both cylinders rotate at the same speed.

Inside the upper cylinder is secured, on the shaft 106, by means of two claws 119, 120, 50 an inker in the shape of a trough 121 whose ends have a slot through which the shaft of the circular brush 122, which supplies the necessary ink for the printing, can pass. This brush has at each end a rubber roller 55 123, 124, whose diameter is slightly smaller than the diameter of the brush, so that by means of levers 125, 126 and 127, it is possible to raise the brush from the bottom of the inker to the rubber rollers in contact 60 with the inner wall of the upper cylinder. During the rotation of this cylinder, the rubber rollers are rotated and the brush, revolving on its shaft sweeps across the inside of the cylinder, imparting ink to its 65 inner surface.

On the support 2 on the right of the apparatus are fixed two cams 128 and 129 (Figure 4) arranged so that the roller 89 is forced, during the rotation of the lower cylinder, to mount successively each of the cams 70 5, thus laterally displacing the rod 84.

On the front part of the apparatus (Figure 4) is fixed a platform 130 having a sliding catch 131 held by an adjustable screw 132 and on which are placed the sheets of 75 paper to be printed.

At the back of the apparatus on the cross bar 133 is a receiver 72 for the sheets after they have been printed.

The apparatus works as follows:— 80

The preceding description shows that when the cylinder C' is rotated by the crank handle M, there is a time when the rod 84, whose roller mounts the cam 129, is forced to the inside of the cylinder. At this instant the membrane 74 is compressed, decreasing the volume of the annular space 74' of the flange 7'.

On further rotation, the roller 89 quickly 90 disengaging the cam 129, allows the rod 84, owing to the spring 86, to take up its original position, and the membrane on relaxing, increases the volume of the annular space of 95 the flange 7', causing a suction through the holes 9, 10 and 11.

The position of the holes, at the moment of suction, is at α (Figure 4) and about two or three millimetres from the upper edge of the sheets on the feeding plate 130.

The sheet nearest the cylinder is then 100 sucked and taken round by the cylinder. The sheet of paper clinging to the holes 9, 10 and 11, prevents any material amount of air from returning to the hollow part of the flange 7' and as the membrane 74 can no 105 longer take up its original position, its rod, by means of rod 95 and the bush 92, will hold the cam 93 against the flange 5', so that fixed cam 100 and the movable cam 93 are 110 no longer continuous. The roller 115 then falls, pulls the lever 112, so that the forks 107 and 108, which contact with this lever, also fall, thus allowing the upper cylinder to engage the lower, and printing the sheet of 115 paper.

When the roller 89, on further rotation, comes against the cam 128, it produces an inverse movement, the membrane is released, and the air expelled through the holes 9, 10 and 11, raises the sheet which is detached 120 from the lower cylinder and projects it on to the receiver 72.

It is thus impossible that the upper cylinder can contact with the lower if for some reason the holes 9, 10 and 11, are not covered by a sheet of paper. 125

On the descent of the upper cylinder, the recorder 134 carrying a pressure button 135 actuated by the finger 136 attached to the fork 108 of the upper cylinder, can only be 130

operated if the upper cylinder descends. The counting of the printed sheets is thus perfectly accurate, and the apparatus can turn without the recorder functioning.

5. The invention is not limited to the details described.

What we claim is:—

1. The combination with automatic duplicating apparatus of a rotary printing cylinder, a pressure cylinder to be applied to a sheet of paper on the printing cylinder, and suction means supported by said printing cylinder for rotation therewith for automatically feeding each sheet of paper and controlling the position of said pressure cylinder.

2. The combination with automatic duplicating apparatus of a rotary printing cylinder, a pressure cylinder to be applied to a sheet of paper on the printing cylinder, a suction chamber communicating with the exterior of said cylinder, suction means including an oscillating lever for creating suction in said chamber and a cam operatively associated with said lever and with said cylinder for operating said lever upon rotation of said printing cylinder.

3. The combination with automatic duplicating apparatus of a rotary printing cylinder, a pressure cylinder to be applied to a sheet of paper on the printing cylinder, and suction means housed within said cylinder and rotatable therewith for retaining said sheets of paper on said printing cylinder, means for preventing said pressure cylinder from being applied to said printing cylinder, said last-mentioned means being controlled by said suction means.

4. The combination with automatic duplicating apparatus of a rotary printing cylinder, a pressure cylinder to be applied to a sheet of paper on the printing cylinder, suction means supported on and rotatable with said printing cylinder for automatically feeding each sheet of paper, said suction being automatically released upon failure of a sheet of paper to be fed to said printing cylinder.

5. The combination with automatic duplicating apparatus of a rotary printing cylinder, a pressure cylinder to be applied to a sheet of paper on the printing cylinder, suction means for automatically feeding each sheet of paper, said suction being automatically released upon failure of a sheet of paper to be fed to said printing cylinder, means operated by the release of said suction for maintaining said pressure cylinder out of engagement with said printing cylinder.

der and means controlled directly by rotations of said cylinder for operating said suction means and creating sheet holding suction anew on such subsequent rotations.

6. In a duplicating apparatus, a printing cylinder, a suction conduit formed with means for maintaining a sheet of paper on said printing cylinder, suction producing means for said conduit comprising a movable suction producing member carried by and rotatable with said cylinder, and operating means comprising fixed elements and parts rotatable with said cylinder for moving said member at certain predetermined periods during the rotation of said cylinder for creating and relieving the suction in said conduit.

7. In a duplicating apparatus, a printing cylinder, a suction conduit formed with means for maintaining a sheet of paper on said printing cylinder, suction producing means for said conduit comprising a movable suction producing member carried by and rotatable with said cylinder, and operating means comprising fixed elements and parts rotatable with said cylinder for moving said member at certain predetermined periods during the rotation of said cylinder for creating and relieving the suction in said conduit, a pressure cylinder, a cam formed with a removable portion, means responsive to the position of said portion for maintaining said pressure cylinder out of contact with said printing cylinder and means responsive to the suction in said conduit for controlling the removal of said removable cam portion.

8. The combination with automatic duplicating apparatus of a rotary printing cylinder, a pressure cylinder to be applied to a sheet of paper on the printing cylinder, a movable diaphragm, obstructing orifices in the printing cylinder, a contact rod operated by the diaphragm and movable along said printing cylinder, an operating lever, fixed cams acted upon by said lever, one of which effects the suction of the sheet and the other its detachment from the cylinder, a movable support for said pressure cylinder displaceable through the movement of said rod and fixed and movable cams acted upon by the lever for controlling said pressure cylinder support, one of said cams being movable by means of said rod.

In testimony whereof we have affixed our signatures.

RENÉ PIERRE ALEXANDRE LE GRAND.
ANTOINE MICHEL GARRET.
